(57) **CLAIM**

The ornamental design for framing square jig, as shown and described.

DESCRIPTION

FIG. 1 is a top plan view of the framing square jig of my new design;

FIG. 2 is a front elevational view thereof, the rear elevational view being a mirror image thereof;

FIG. 3 is a bottom plan view thereof;

FIG. 4 is an end elevational view of the left end thereof;

FIG. 5 is a sectional view taken along line 5—5 of FIG. 1;

FIG. 6 is a sectional view taken along line 6—6 of FIG. 2;

FIG. 7 is a sectional view taken along line 7—7 of FIG. 1;

FIG. 8 is an end elevational view of the right end thereof;

FIG. 9 is a top plan view of the framing square jig of FIG. 1 combined with a square;

FIG. 10 is a front elevational view of FIG. 9;

FIG. 11 is a rear elevational view of FIG. 9;

FIG. 12 is a bottom plan view of FIG. 9; and,

FIG. 13 is an end elevational view of FIG. 9, the opposite end being a mirror image thereof.
